APPARATUS FOR FINISHING AND MOUNTING
TERMINALS ON LAMP BULBSGeorge E. Algatt, Allentown, and Willard G. Otto,
Schoencksville, Pa., assignors to Western Electric Com-
pany Incorporated, New York, N.Y., a corporation of
New YorkFiled June 2, 1961, Ser. No. 114,439
8 Claims. (Cl. 29—25.19)

This invention relates to apparatus for finishing and mounting terminals on lamp bulbs, more particularly, switchboard lamp bulbs.

In an apparatus for manufacturing switchboard lamps, the lamp bulbs are supported in finishing bars, as shown in applicants' co-pending application, Serial No. 114,441, filed June 2, 1961, which are moved relative to apparatus at different stations to complete and test the lamps. The first of the finishing steps, through the aid of the finishing bars, includes the partial formation of the terminals followed by the finishing of the terminals and the utilization of the finishing bars to hold the terminals in place after they have been provided with a suitable conductive cement and moved into accurate positions relative to the lamp bulbs.

An object of the present invention is an apparatus which is simple in structure and highly efficient in finishing and mounting terminals on lamp bulbs.

In accordance with the object, the apparatus includes an arm mounted for movement between a finishing position and a mounting position and carrying a finishing tool adapted to finish forming the terminal, a cutter also being carried by the arm and adapted to cut each finished terminal from a strip of partially formed terminals so that when the arm is moved into the mounting position, the finished terminal will be mounted on the lamp bulb.

More specifically, a suction means is incorporated in, and associated with, the forming tool to hold the finished terminal in engagement with the forming tool during the mounting of the terminal on the bulb. Also, a companion element disposed adjacent the finishing position is operable first, in cooperation with the finishing tool to assist in finishing the forming of each terminal, and to cooperate also with the cutter to cut the finished terminal from the strip.

Other objects and advantages will be apparent from the following detailed description when considered in conjunction with the accompanying drawings wherein:

FIG. 1 is a side elevational view of the apparatus;

FIG. 2 is a fragmentary side elevational view of portions of the apparatus at the end of the finishing operation and prior to the cutting operation;

FIG. 3 is a view of the structure shown in FIG. 2 at the end of the cutting operation with the companion element extended;

FIG. 4 is a view of the structure shown in FIG. 3 with the companion element contracted; and

FIG. 5 is a fragmentary side elevational view of the portions of the arm, the finishing tool, and a backing element at the end of the mounting movement.

The apparatus, as shown in FIG. 1, includes a table 10 mounted at a given position relative to a guide 11 for a series of successive finishing bars 12, as disclosed in the aforementioned co-pending application. Each bar has 32 finishing positions disposed at equally spaced positions longitudinally of the bar for receiving and supporting lamp bulbs 14. The lamp bulbs are supported between pairs of resilient conductive members 15. Furthermore, the bars are constructed so that the equal spacing of the finishing positions will continue from one bar to another permitting the advancement of the bars during

2

like time intervals with like rest intervals, wherein the bulbs will be positioned successively at what may be called a mounting station where they will receive the terminals singly.

A metallic strip, indicated generally at 17, containing partially formed terminals, is advanced intermittently along a guide 18, the distance of the length of each terminal, beneath a cutter 19 which is secured by set screws 20, an aperture of a supporting bracket 21 mounted at 22 on the table 10. The cutter 19 may be adjusted in its aperture by a screw 23 so that its cutting edge will be located relative to a finishing position of an arm 25, shown in solid lines in FIG. 1, the broken line position of the arm indicating its approach to the mounting position shown more clearly in FIG. 5.

The arm 25 is of the contour shown in FIG. 1 fixedly mounted on a spindle 26 which is journaled in suitable bearings in the bracket 21. The upper portion of the arm 25 is formed with a guideway 27 square in cross-section in spaced members 28 and 29 secured in place by screws 30. A finishing tool 32 is frictionally mounted in the guideway 27 of the arm.

The finishing tool has a lower end 33 provided with companion angularly positioned surfaces 34 and 35 to produce a finishing bend in end portions 36 of terminals 37. The finishing tool also has passageways 38 and 39 extending in parallel positions from suction ports at the surfaces 34 and 35, respectively, to a main passageway 40 in the forming tool. The passageway 40 is connected by suitable means, not shown, to a suction line 41 which is under constant suction.

An adjustable stop 49, carried by an extension 50 of the bracket 21, controls the location of the arm 25 in the finishing position. The means to move the arm to the mounting position, shown substantially in FIG. 5, includes a cam 51 mounted on a cam shaft 52. The cam shaft 52 is driven in timed relation with the moving means for the finishing bar so that a terminal may be finished and mounted on the successive lamp bulbs while they are at rest in the mounting position. The cam 51 is adapted to rock a lever 53, the right end of which is pivotally supported at 54 by a bracket 55 through engagement with a cam roller 56 to move a link 57 connecting the left end of the lever 53 with a lever 58 which is fixedly mounted on the shaft 26. A spring 59 connecting the link 57 with a fixed position member 60, supported by the table 10, serves as a power means to force the arm 25 from the mounting position to the finishing position while the roller engages a low portion (not shown) of the cam 51.

Before the arm is moved from the finishing position to the mounting position, operations are performed to finish the forming of the terminal and to cut it from the strip 17. A backing element 62 is mounted in the arm 25 with a lower edge of an inner surface 63 in a plane with the edge of the cutter 19. The finishing tool 32, frictionally held in the guideway 27 of the arm, is subject to movement downwardly through the action of a cam 65 mounted on the cam shaft 52 and to movement upwardly by a companion cutter element 66 slidably mounted in a guideway 67 of the bracket 21. The cutting operation is performed by the cutter 19 and the cutter element 66.

The cam 65 is adapted to rock a lever 68 about an axis of a spindle 69 on which it is mounted by engaging a cam follower or roller 70 mounted on the lower end of the lever. The spindle 69 is rotatably supported by a bracket 71 mounted at 72 on the table 10 adjacent an aperture 73 in the table, through which the lever extends and in which the lever is free to move. The spindle 69 has a lever 75 fixed thereto and provided with an adjust-

able head 76 positioned to engage a roller 77 mounted on the outer end of the finishing tool when the finishing tool is located with the arm 25 in the finishing position. Therefore, the cam 65 is adapted to operate the levers 68 and 75 to cause movement of the finishing tool 32 downwardly in the direction of the arrow 78, FIG. 2, to the position shown in this figure. A spring 79, connected to the lever 68, provides the force to rock the levers 68 and 75 clockwise when permitted by a low portion, not shown, of the cam 65.

A spring 80 having one end connected to a fixed member 81, mounted on the undersurface of the table 10, has its other end connected to the companion element 66 to cause a roller 82 to engage an adjustable head 83 of a lever 84 and to serve to return the companion element from an operated position, shown in FIG. 3, to its normal position, shown in FIG. 1. The lever 84 supports the head 83 in any desired adjusted position to control the extent of the operative movement of the element 66 and is fixedly mounted on a spindle 85. The spindle 85 is supported by a bracket 86 secured at 87 to the undersurface of the table 10. The upper end of a cam lever 89 is fixed to the spindle 85 while the lower end of the lever supports a cam follower or roller 90 held by the spring 80 in engagement with a cam 91 mounted on the cam shaft 52.

Operation

Beginning with the apparatus, in the position shown in FIG. 1, with the arm 25 in its finishing position and the forming tool 32 and the companion cutting element 66 in their normal or open positions, the strip 17 is advanced by suitable means, not shown, to locate the next partially formed terminal connected thereto in a position where this terminal may be finished and mounted through a single cycle of operation of the apparatus. At this time, the finishing bar 12 is moved to present the next bulb in the mounting station.

The cams 51, 65, and 91 function in their proper orders, first, to cause the cutting element 66 to move into the position shown in FIG. 2 after which the finishing tool 32 is moved to the position shown. In other words there is a pause of the element 66 at FIG. 2 until the finishing tool finishes forming the terminal, at which time, the element 66 continues its upward movement to cut the terminal with the cutter 19 from the strip 17.

The contours of the cams 65 and 91 are such that this upward movement of the element 66 will push finishing tool 32 to its upward position with the cam 65 maintaining a holding force to locate the cut end of the terminal in engagement with a surface 63 of the element 62. When this portion of the operating cycle of the element 66 has been completed, the spring 80 will function to return the element 66 to its normal position through the control of its cam 91.

At this time, with the terminal 37 held by the finishing tool in a position where it has been pushed by the element 66, the arm 25 is rocked by its cam 51 into the position shown in FIG. 5 where the finished terminal is forced between the bulb 14 and the adjacent resilient member 15. This action is assured not only by the suction means embodied in the furnishing tool, but by the assistance of the backing element 62 engaging the upper end of the terminal and forcing the terminal into position.

Although the suction is applied to the ports through the passageways 38 and 39 continuously, and is sufficient to maintain the terminal on the finishing tool during mounting of the terminal, the gripping force of the conductive member 15 is sufficient to break this connection.

This illustrates the mounting of a terminal on one side of each bulb. In actual practice, there are two apparatus, identical in every way with exception that one is positioned to mount a terminal on one side of each lamp

bulb, while the other is positioned to mount the terminal on the other side of each lamp bulb.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

10. An apparatus for finishing and mounting terminals, partially formed in a strip, on lamp bulbs moved successively to a mounting station in holders having resilient members disposed on the holders adjacent the lamp bulbs comprising an arm, means to support the arm for movement between a finishing position and a mounting position, a finishing tool carried by the arm and adapted to finish forming each terminal, a cutter carried by the arm and adapted to cut each finished terminal from the strip, means for guiding the strip relative to the finishing tool, and means to move the arm to the mounting position to cause mounting of the terminal on a lamp bulb at the mounting station.
15. An apparatus according to claim 1 in which an element is actuatable to assist the finishing tool in finishing the forming of the terminals and to assist the cutter in cutting the terminals from the strip.
20. An apparatus according to claim 1 in which the finishing tool is movably carried by the arm and has a terminal engaging end of a predetermined contour adapted
25. to engage one side of the terminal, an element adapted to engage the other side of the terminal and assist the tool in finishing the formation of the terminal, and means actuatable to move the tool relative to the arm toward the element.
30. An apparatus according to claim 1 in which means supports the element for movement relative to the finishing tool, and means operable to cause movement of the element to engage the partially formed terminal and assist the tool in finishing the terminal short of the cutter.
35. An apparatus according to claim 3 in which means supports the element for movement relative to the finishing tool, and means operable to cause movement of the element a given distance to engage the partially formed terminal and assist the tool in finishing the terminal short of the cutter and operable to cause further movement of the element and the tool to move the terminal relative to the cutter to cut the finished terminal from the strip.
40. An apparatus according to claim 1 in which a suction port is disposed in the finishing tool at a terminal engaging surface thereof, and a suction control means connected to the suction port and rendered effective to hold the terminal on the tool while being finished and to release the terminal when mounted.
45. An apparatus according to claim 5 in which suction ports are disposed in the terminal engaging end of the finishing tool, and a suction control means connected to the suction ports and rendered effective to hold the terminal on the tool while being finished and to release the terminal when mounted.
50. An apparatus according to claim 3 in which the moving means for the finishing tool moves the tool in one direction until the terminal engaging surface thereof engages one side of the terminal and the element engages an opposing side of the terminal to assist the tool in finishing forming the terminal, and means to cause movement of the element in a direction opposing said direction of movement of the tool to first assist the tool in the final forming of the terminal and to move the terminal and tool relative to the cutter to assist in cutting the terminal from the strip and to position the tool supporting the terminal in the arm for mounting of the terminal on the lamp bulb.
